SAFETY DEVICE.
FILED FEB. 8, 1919.

UNITED STATES PATENT OFFICE.

CHARLES M. BRADFORD, OF BOSTON, AND DARIUS W. BUNKER, OF BROOKLINE, MASSACHUSETTS, ASSIGNEES TO UNITED SHOE MACHINERY CORPORATION, OF PATERSON, NEW JERSEY, A CORPORATION OF NEW JERSEY.

SAFETY DEVICE.

Application filed February 8, 1919. Serial No. 275,846.

To all whom it may concern:

Be it known that we, CHARLES M. BRADFORD and DARIUS W. BUNKER, citizens of the United States, and residents of Boston, in the county of Suffolk, and Brookline, in the county of Norfolk, and State of Massachusetts, respectively, have invented certain Improvements in Safety Devices, of which the following description, in connection with the accompanying drawings, is a specification, like reference characters on the drawings indicating like parts in the several figures.

This invention relates to safety devices and is herein illustrated as embodied in a guard designed for use with a leather splitting machine.

A leather splitting machine commonly comprises a knife to which the pieces of leather are fed by a pair of feed rolls, and a table upon which the pieces are placed one by one and over which they are pushed by the operator to present them to the feed rolls. The pieces of leather which are to be split vary greatly in length and in thickness; but, for the purpose of explaining the present invention, top lifts and soles will be considered as representing the extreme limits. Toplifts are commonly not more than three inches in length and a quarter of an inch in thickness while soles are often several times that length and twice that thickness. It should be understood that these figures are not intended to be accurate and are used merely to make clear a problem which is encountered when an attempt is made to prevent injury to the fingers of the operator and at the same time to interfere in no way with the operation of the machine.

When top lifts are being operated upon, any guard which is used should be fairly close to the feed rolls so that the short lifts may be presented to the bite of the rolls; it should also be as close as possible to the upper surface of the table so as to prevent the operator from sticking the tips of his fingers through the opening between the guard and the table through which the lifts are presented. When soles are to be operated upon, the opening between the guard and the table should be increased; but, this increased space will permit the operator's fingers to pass through it with the consequent danger of being caught between the

feed rolls; and if, instead of increasing the space between the guard and the table, the guard is merely moved farther away from the rolls, a thick sole cannot be presented to the machine.

According to one feature of the invention there is provided a guard located adjacent to the mechanism to which the work is to be presented, and means whereby the distance of the guard from the mechanism and the extent of the opening through which the work is presented may be varied. In the illustrative machine the guard, which is located in front of the feed rolls and above the table, is adjustable toward and from both the rolls and the table. If top lifts are to be operated upon, the guard is adjusted close to the feed rolls and to a height above the table just sufficient to permit the top lifts to be presented but insufficient to permit the tips of the fingers of the operator to pass beneath it. If, thereafter, a lot of soles is to be run through the machine, the guard is adjusted to a distance from the rolls greater than the length of the operator's fingers and to a height above the table sufficient to permit the thickest soles to be presented. This thickness is less than the thickness of the operator's hand; and consequently, even though the operator may stick his fingers through the opening between the guard and the table, he cannot reach with them to the feed rolls.

In order to simplify the manipulation of the guard, another feature of the invention relates to a construction whereby adjustment of the guard in one of the directions indicated automatically adjusts it properly in the other direction. In the illustrative machine, the guard is adjustable over the table toward and from the feed rolls, there being a guideway to control this adjustment so shaped that, when the guard is close to the rolls, the opening between it and the table is small, and when the guard is moved farther from the rolls, the size of the opening is increased. Consequently, whether soles or top lifts are being operated upon, the guard is always in a position to prevent the operator's fingers from being caught between the rolls.

These and other features of the invention including certain details of construction and combinations of parts will be described as

embodied in an illustrative machine and pointed out in the appended claims.

Referring now to the accompanying drawing,

5 Figure 1 is an end elevation partly in section of a leather splitting machine equipped with one embodiment of the invention, and

Figure 2 is a front elevation of a portion of the same machine.

10 The leather splitting machine chosen for illustration comprises a frame 3, upper and lower feed rolls 5 and 7, a knife 9 and a table 11, the table being pivoted to the frame at 13 and angularly adjustable by means of a set screw 15. The rolls are driven continuously in a direction to feed the work to the knife; and the position of the upper roll is determined by wedges 17 mounted upon a horizontally adjustable bar 19. The parts 20 thus far described are old and well known and may be identical with corresponding parts of similar machines, such for example as that shown and described in the patent to Nash No. 894,850. The machine per se 25 forms no part of the present invention and has been chosen first because it represents generally a type in which presentation of the work is accompanied with some danger and second because operation of it involves a 30 particular danger due to the different dimensions of the pieces of work which are commonly fed through it.

As has been explained, it is usual to employ leather splitting machines to operate 35 upon pieces of work, such as top lifts and soles, which differ greatly in length and in thickness; and one object of the present invention is to ensure that neither small pieces such as top lifts nor large pieces such as 40 soles can be presented to the machine except under conditions which are safe to the operator. To this end the table 11 has on each side upstanding flanges 21 in the outer side of each of which is formed a groove 23.

45 Horizontally these grooves register, each groove being a counterpart of the other. Referring to Fig. 1, in which one of the grooves is shown complete, it will be seen that, beginning at the end nearer to the feed rolls, there is first a substantially horizontal portion, then an upwardly inclined portion, then a second horizontal portion higher than the first, and finally a semi-circular portion in which the direction of extent of

55 the groove is practically reversed to form, as will presently be described, a stop wall. The guard 25 is in the form of a bar having a curved face to permit it to be adjusted, as shown, close to the upper feed roll and depending arms, one at each end, each arm having a substantially upright portion 27 and a base 29. Rotatably mounted on each base and extending respectively into the grooves 23 are a forward roller 31 and a rearward roller 33. When the guard

is in the position shown, the rollers 31 are in the forward ends of the grooves. In this position the opening between the bottom of the guard and the table is sufficient to permit the thickest top lift to pass through it 70 but insufficient to permit the ends of the fingers of the operator to pass through. Consequently the operator may feed short pieces, such as top lifts, to the rolls without danger. If, now, it is desired to present soles to the machine, the guard is pulled back to the dotted line position shown in Fig. 1, the rear rollers 33 in this position engaging the end walls of the reversely curved portions of the grooves. In this position the guard is tilted and raised considerably above the table so that the opening between the guard and the table is greater than before. When the device is used with a splitting machine, this opening 80 is about five-eighths of an inch in height, and the guard is located about six inches from the rolls so that even if the operator pushes his fingers through the opening he 85 cannot touch the feed rolls.

90 The reason for the shape of the guideway formed by the grooves 23 will now appear. Because of it the operator cannot place the guard in a dangerous position. As long as the forward rollers 31 are in the forward 95 ends of the grooves and the guard is within finger length of the rolls, the opening between it and the table is insufficient to permit the passage of the operator's fingers; and not until the guard has reached a position more than finger length from the rolls is it raised sufficiently to permit the operator's fingers to pass beneath it. In no position of the guard can the operator pass his fingers beneath it into contact with the 100 rolls.

105 In order to ensure that an operator shall not be able to reach over the top of the guard at any time and thereby risk catching his fingers between the feed rolls, a 110 shield 37 is hinged at its rear end to a rod 39 which is carried by the arms 27, the forward end of the shield being held up against a stationary part 43 of the machine by a coiled spring 41 wound about the rod 115 and having one end resting upon the top of the guard and the other pressing up against the under side of the shield.

120 Having thus described the invention, what we claim as new and desire to secure by Letters Patent of the United States is:

1. The combination with mechanism to which pieces of work are presented by an operator, of a table upon which the pieces are placed and over which they are presented, of a stationary finger guard located in front of the mechanism and spaced from the table to permit the work to pass between the guard and the table, and means whereby the space between the guard and the table may 125 130

be increased by adjusting the guard over the table in a direction away from the mechanism.

2. The combination with mechanism to which pieces of work are presented by an operator, of a table upon which they are placed and over which they are presented, a guard located between the operator and the mechanism and spaced from the table to permit the work to pass beneath it, said guard being stationary while in use but adjustable into different positions, and means whereby said guard may be adjusted toward the operator and at the same time away from the table.

3. The combination with mechanism to which pieces of work are presented by an operator, of a table, a guard between which and the table the pieces are presented, the guard being stationary while in use but adjustable over the table from one operative position adjacent to and in front of the mechanism to another operative position more remote from but still in front of the mechanism, and means whereby the distance between the guard and the table increases as the guard is adjusted from the first-named to the second-named position.

4. The combination with mechanism to which pieces of work are presented by the operator, of a table, a guard between which and the table the pieces are presented, the guard being stationary while in use but adjustable toward and from the mechanism, and means for guiding the guard in its adjustment constructed and arranged to increase the extent of the opening between the guard and the table when the guard is adjusted away from the mechanism.

5. The combination with feed rolls to which pieces of work are presented by the operator, of a table for supporting the pieces, a guard located in front of the rolls and above the table, said guard being stationary while in use but adjustable into different positions, a support for the guard, two sets of aligned guide members carried by the support, and two registering guideways in which the guide members are adapted to travel, the guideways being shaped to tilt the support and thereby to increase the space between the guard and the table when the support is moved away from the rolls.

6. The combination with a machine adapted to operate upon short, thin pieces of stock and longer, thicker pieces, of a table, a guard located in front of the operative mechanism of the machine and spaced above the table to form an opening through which the operator presents the pieces to the

mechanism, said guard being adjustable over the table toward and from the mechanism, and means for controlling the adjustment constructed and arranged to maintain the opening of a size sufficient to prevent the fingers of the operator from passing through it in all positions of the guard which are within finger length of the mechanism.

7. The combination with splitting mechanism to which pieces of work are presented by an operator, of a table, a guard between which and the table the pieces are presented, a guideway, and means carried by the guard and adapted to travel along the guideway, said guideway having two runs substantially parallel to the table and an inclined connecting run.

8. The combination with splitting mechanism to which pieces of work are presented by an operator, of a table, a guard between which and the table the pieces are presented, and means whereby the guard may be adjusted into and held in two operative positions, one farther from the operator and nearer to the table and one nearer to the operator and farther from the table.

9. The combination with mechanism to which pieces of work are presented by an operator, of a guard, means whereby the distance of the guard from the mechanism may be varied, and a shield movably mounted upon the guard and arranged to prevent the operator from reaching over the guard.

10. The combination with mechanism to which pieces of work are presented by an operator, of a guard, means whereby the distance of the guard from the mechanism may be varied, and a shield movably mounted upon the guard and arranged to prevent the operator from reaching over the guard, said shield comprising a plate fastened to the guard and slidably over a part of the machine.

11. The combination with splitting mechanism, of a guard in the form of a plate located in front of said mechanism, a table between which and the guard pieces of work may be presented, means whereby the guard may be adjusted toward and from the splitting mechanism in the general direction of the feed of the work as well as toward and from the table, and a shield adjustable with the guard and arranged to prevent at all times the operator from reaching over the guard.

In testimony whereof we have signed our names to this specification.

CHARLES M. BRADFORD.
DARIUS W. BUNKER.
